UNITED STATES PATENT OFFICE

2,645,964

APPARATUS FOR OPERATING RAILWAY
DUMP CARSTheodore J. Kochaver, Virginia, Minn., assignor
to United States Steel Corporation, a corpora-
tion of New Jersey

Application July 30, 1951, Serial No. 239,365

3 Claims. (Cl. 81—54)

1

The present invention relates to railway car operating equipment and more particularly to an apparatus for mechanically actuating the hopper mechanisms of bottom-dump railway cars.

Prior to my invention the operating mechanism of hopper cars, which usually consisted of a main dump shaft and pinion keyed thereto which operated the hopper door operating gears, was actuated manually by workmen who applied a wrench or similar tool to the end of the dump shaft and rotated the same to either open or close the hopper doors. This practice at best was dangerous and time-consuming. This manual method of operation was particularly disadvantageous where a large number of bottom-dump cars were to be handled in a short period of time such as cars used for carrying iron ore to crushers and concentrators.

It is accordingly an object of my invention to provide apparatus for mechanically operating the dumping mechanism of railway hopper cars in a safe and speedy manner.

These and other objects will become more apparent after referring to the following specification and attached drawings, in which:

Figure 1 is a plan view;

Figure 2 is a view taken on the line II—II of Figure 1;

Figure 3 is a view taken on the line III—III of Figure 2 showing the apparatus in operation with a hopper car; and

Figure 4 is a sectional view taken on the line IV—IV of Figure 3.

Referring more particularly to the drawings, reference numeral 2 indicates a base member mounted on four railway car wheels 4 adapted to move along a narrow gauge track 6 positioned parallel to a track 8 used for movement of hopper cars. A pair of spaced vertical supports 10 project upwardly from the top surface of the base 2 intermediate its ends. A hole 12 is provided through the upper portion of each of the supports 10 to accommodate the ends of a rotatable shaft 14 which supports an elongated platform 16 at a point intermediate its ends. Platform 16 may be provided with a number of aligned holes 17 so that the position of the shaft 14 may be changed to vary the pivot point of the platform.

The forward end 18 of the platform 16 is provided with a pair of spaced bearings 20 which project from the sides of the platform. A hollow drive shaft 22 is carried between the bearings 20 with its ends projecting therethrough. An

2

elongated coupling 26 having a socket 28 on one end is slidably fitted at its other end 30 by means of a spline connection in the bore of the shaft 22. The end 30 of the coupling 26 is substantially square in shape and is only slightly smaller in cross sectional area than the bore of the shaft 22 so that it may slide therein and at the same time rotate along the shaft when it is rotated. Since different type railway hopper cars vary in width it is necessary that coupling 26 be transversely adjustable relative the platform 16. Thus, when a wide car is to be operated, the coupling 26 is moved inwardly within the bore of the shaft 22 and when a narrower car is to be serviced the coupling is moved outwardly.

The opposite projecting end of the shaft 22 is provided with a sprocket wheel 32 around which extends one end of an endless drive chain 34. The opposite end of the drive chain 34 is mounted around the sprocket wheel 36 keyed to the shaft of a reversible electric motor 38 which is disposed on the upper surface of the platform 16 remote from the bearings 20.

A panel board 40 projects upwardly from the end 18 of the platform 16 and carries a control switch 42 for controlling the motor 38.

The height of the dump shaft is not the same on all railway cars and therefore it is necessary to provide means whereby the operating height of the coupling 26 may be varied to accommodate the various size hopper cars. A screw jack 44 which pivots the platform 16 is provided for this purpose. The screw jack 44 having a hand wheel 46 is attached at one end to the underside of the end 18 of the platform 16 and is pivotally attached at its opposite end between a pair of brackets 48 affixed to the forward end of the base 2. Rotation of the hand wheel 46 causes the screw jack to pivot the platform 16 to either raise or lower the end 18 in order to place the coupling 26 in operating position.

In operation the apparatus is rolled on the track 6 to a point adjacent the dumping station where it is desired to unload the contents of the hopper cars. A hopper car W is spotted on the track 8 adjacent the car trapper. The height of the platform 16 is adjusted by means of the screw jack 44 until the coupling 26 is positioned opposite the dump shaft X of the car W and the coupling is adjusted as described above until the socket 28 engages the end of the dump shaft. The switch 42 is then operated to actuate the motor 38 which in turn rotates the drive chain 34 to rotate the drive shaft 22 which in turn causes the coupling to turn the

shaft **X**. Rotation of the shaft **X** opens the hopper doors **Y** of the car **W** in the customary manner. After the contents of the car have been dumped the switch **42** is again actuated to reverse the motor **38** which reverses the rotation of the drive shaft **22** and the dump shaft **X** to close the hopper doors. The coupling **26** is then disengaged from the end of the dump shaft **X** and another car is moved into position whereupon the operation is repeated.

While one embodiment of my invention has been shown and described it will be apparent that other adaptations and modifications may be made without departing from the scope of the following claims.

I claim:

1. Apparatus for operating the dump actuating shaft of a bottom-dump railway hopper car comprising a base member, a pair of spaced vertical supports projecting upwardly from said base member intermediate its ends, an elongated platform pivotally mounted between and supported at a point intermediate its ends by the upper portions of said supports, means for pivoting said platform whereby the heights of the ends thereof are adjusted relative to said base, a pair of spaced bearings attached to and projecting from one end of said platform, a hollow drive shaft rotatably carried between said bearings with its ends projecting therethrough, an elongated coupling having one end slidably inserted in the bore of said shaft and its other extending out-

wardly of one of the projecting ends of said drive shaft for engaging the end of said dump shaft, said coupling being adapted to be moved for longitudinal adjustment within said bore, and drive means connected with said shaft for rotating the same to thereby turn said coupling.

2. Apparatus for operating the dump actuating shaft of a bottom-dump railway hopper car as defined in claim 1 in which said drive means include a sprocket wheel secured to the projecting end of said drive shaft remote from said coupling, motor means mounted on said platform, and an endless drive means connecting said sprocket and said motor means.

3. Apparatus for operating the dump actuating shaft of a bottom-dump railway hopper car as defined in claim 2 characterized by said base member being wheel mounted for movement along a track.

THEODORE J. KOCHAVER.
